UNITED STATES PATENT OFFICE.

ARTHUR E. ALLISON, OF COATESVILLE, PENNSYLVANIA.

INCUBATOR.

1,231,112.

Specification of Letters Patent. Patented June 26, 1917.

Application filed August 12, 1913. Serial No. 784,349.

To all whom it may concern:

Be it known that I, ARTHUR E. ALLISON, a citizen of the United States, and a resident of Coatesville, Chester county, Pennsylvania, have invented certain Improvements in Incubators, of which the following is a specification.

My invention relates to apparatus employed for the artificial incubation of eggs, and the main object of my invention is to provide a structure that is entirely automatic in its action, being operated by the force exerted by a volume of liquid under suitable head, which liquid may be a hydrocarbon fuel to be subsequently fed to a suitable burner to provide the necessary heating of the structure.

These and other features of my invention are more fully described hereinafter, reference being had to the accompanying drawings, in which:

Fig. 1, is a side elevation of an incubator made in accordance with my invention;

Fig. 2, is a sectional elevation on the line II-II, Fig. 1;

Fig. 3, is a sectional plan view on the line III-III, Fig. 2;

Fig. 4, is an enlarged view, partly in section on the line IV-IV, Fig. 2, and

Fig. 5, is a detail view of part of Fig. 4.

My improved incubator comprises a suitable frame or structure 1 supported by legs 2, and such structure may be circular in cross sectional contour. A platform 3 is provided for the support of the heating means 4, and the egg chamber is closed by a top or cover 5. The egg chamber properly comprises a fixed base or platform 6, carrying the eggs to be incubated and surrounded by an annular wall or casing 7 adapted to telescope within the upper portion of the structure indicated by the annular wall or casing 7^a. This movement of the casing 7 takes place at intervals and permits the desired airing of the eggs. The means for operating this part of the structure are more particularly referred to hereinafter and they may be timed so as to have the extent of airing of greater or less duration as may be necessary or desirable. The lamp burner or other heating device 4, preferably a burner structure designed to gasify the hydrocarbon or other liquid fuel employed, may be centrally disposed with respect to the structure, being carried by the platform

3, and leading from this burner is the usual chimney 9, surrounded by a heat chamber 10; the latter communicating via apertures 11 with the upper portion of the incubating chamber. The casing 7 of this chamber is raised and lowered at regular intervals as hereinafter described, and during the raising or lowering operation, preferably the former, the eggs are turned by a special turning device, more particularly described hereinafter.

The operation of the structure is entirely automatic, and for this purpose the following mechanism is employed: 15 represents a tank containing a suitable liquid, which may be hydrocarbon fuel, kerosene or similar material employed as the heating means, or water or other liquid, which delivers by way of a pipe 16 through a straightway 76 valve 17, a three-way valve 18, and a short pipe section 16^a to a chamber 19, suitably supported by the frame or casing of the machine; which chamber 19 contains a piston 20 carried by a piston rod 21, and these parts 20 and 21 are raised by the force imparted by the head of liquid entering the chamber 19 below the piston 20. To the lower end of the piston rod is connected a cord 22, attached to and passing partly 75 around a sheave 23 carried by a shaft 24. Carried by said shaft is a second sheave 23^a to which is attached a second cord 22^a which passes around a sheave 25 mounted on the axis of the egg carrier; the opposite end of said latter cord passing over another sheave 26 supported by a bracket 27 secured to the egg support 6, and has at its lower end a weight 28. In addition, the shaft 24 carries a pair of sheaves 29 to which cords 30 80 are attached which pass over sheaves 31 carried by studs 32 supported by the frame of the structure, the opposite ends of which cords are connected at 33 to tubular arms 34 carried by the movable portion 7 of the egg chamber, and when the shaft 24 is turned by means of the cord 22 through the medium of the piston and piston rod, the sheaves 29 will be turned to raise the casing 7 of the egg chamber to a point substantially at or near the top of the casing. It will be understood, of course, that other equivalent means may be employed to effect movement of the casing 7, for instance rack and pinion connections.

Within the egg chamber and disposed directly over the egg support or base which is

grooved to accommodate the eggs, is an egg turner, comprising an open frame 35 containing spacing partitions for the eggs, which frame is centrally journaled and carries the sheave or pulley 25 around which the cord 22^a passes. As the piston raises the cord 22, the shaft 24 with the sheave 23^a will be turned and the latter will wind up the cord 22^a so as to rotate the frame 35, and the eggs being positioned by said frame, the same will be turned as desired. Upon the lowering of the piston 20 due to flow of the liquid from the chamber 19, the weight 28 will take up the slack in the cord 22^a. 15 a: d in practice such cord will slip around the sheave 25 of the egg turning device so that no unnecessary movement is imparted thereto. Should the sheave be turned, however, effecting movement of the egg carrier, 20 no harm will be done to the eggs. The movement of the egg carrier is simultaneous with the lifting of the casing 7.

As the chamber 19 fills with the liquid, the piston rod 21, which carries an arm 36 24 at the side adjustably connected to a vertical rod 37, is raised; said rod 37 being operatively connected, by means of a pin 38, with a slotted arm 39 of a three-way valve 40, shifting the position of the latter from that shown in Fig. 4; the three-way valve 30 18 remaining in the original position so that the liquid will bypass around the valves 17 and 18 via pipes 16^b and 16^c through said three-way valve 40 and pipe 41 to the 35 lower end of a chamber 42, having a piston 43 and piston rod 44. Liquid is also supplied to said chamber 42 by an extension of said bypass pipe 16^b to the upper side of this piston 43, but the area of the lower side 40 being greater, the piston will rise under the force exerted by the head of the liquid passing through the pipe 41.

The valve 18 has an arm 45, with a pin 46 for engagement with a slotted portion 47 of the piston rod 44 so that as the latter rises, the valve 18 will be turned in its seat, permitting flow of the liquid (fuel) from the chamber 19 via a pipe 48 to a chamber 50, from which it passes by a pipe 51 to the 50 burner of the heating device 4.

Upon entering the chamber 50, the initial flow of the liquid preliminarily raises an auxiliary float 52 pivoted at 53, and upon the further rise of the liquid, a second float 55 carried by a rod 56 and having a slotted connection 57 with the pivoting spindle of the auxiliary float, rises; the auxiliary float 52 having a projection or catch 58 for engagement with the slotted connection of the 60 second float 55 to lock the same in the elevated position after it has risen with the entering liquid so that the lowering of the liquid (fuel) by reason of the burning of the same or other removal thereof will not 65 affect the position of said float 55 nor change

its condition until the auxiliary float 52 drops away by the lowering of the liquid; thereby withdrawing its projection or catch 58 from engagement with the slotted connection 57 of said float 55. (As shown in Fig. 4, both floats 52 and 55 are in the 70 lower position.)

The rod 56 of the float 55 is connected at its upper end to one end of a lever 61 pivotally mounted at 62, the opposite end of which lever is connected by means of a link 63 to an arm 64 of the valve 17, and upon the rise of said float 55, this lever will be operated to shift the valve 17 and cut off the supply of liquid (fuel) flowing from 80 the main reservoir 15 to the chamber 19.

As the liquid flows from the chamber 19 through the valve 18 in its changed position, the piston 20 and piston rod 21 will lower with the rod 37 and finally close the 85 valve 40, and pressure being relieved from the underside of the piston 43 in the chamber 42, said piston will lower by reason of the pressure entering via the bypass 16^b from the pipe 16, lowering the piston rod 90 44, and through its connection with the handle 45 of the valve 18, will shift the latter so as to open communication between said pipe 16 and the chamber 19. This communication will commence as soon as the 95 float 55 in the chamber 50 lowers sufficiently to open the valve 17, and upon full opening of the latter, the chamber 19 will fill and the entering fluid will act upon and raise the piston 20 therein so that the parts will 100 undergo the same operation as above set forth.

The liquid (fuel), it will be noticed, flows away from the chamber 19 as soon as communication is established with the chamber 50, so that the piston in said chamber 19 will drop and the other parts will be restored to their normal position ready for a fresh supply of liquid (fuel) to be fed in the manner indicated as soon as the liquid (fuel) chamber 50 feeding the burner or other heating device empties. This same condition will proceed as long as the chamber 15 is supplied with the desired head of liquid. It is desirable, of course, that the 115 amount of liquid contained in the chamber 15 shall be sufficient for the usual time required to hatch various kinds of eggs by incubation, thirty-one days for instance. For the hatching of hens' eggs it requires 120 twenty-one days, and ducks' eggs twenty-eight days.

It is, of course, desirable to employ a thermostat to regulate the amount of heat delivered to the incubating chamber, and I 125 have shown at 60, more or less diagrammatically, such device which may be connected by any suitable means with the burner controlling handle 61, such for instance as providing the latter with a pinion 62 to be en- 130

gaged by a rack rod 63 actuated from the thermostat through the medium of a lever 64, having a gear segment 65 in operative engagement with the upper end of the rack 5 rod 63.

5 The passage of liquid from the chamber 19 to the chamber 50 can be regulated to feed slowly so that the time of raising and lowering the shell or casing can be set for ten minutes, for instance, or for any other 10 length of time desirable for giving the eggs a proper airing.

The feed chamber and other chambers may be of such a size and capacity that they 15 will fill twice during each twenty-four hours; the casing being lifted for airing and the eggs being turned each time the feed chamber is filled.

When fuel of an oily nature is employed 20 as the operating means, it will serve in a greater or less degree to effect lubrication; insuring the ready operation at all times of the moving parts.

After starting the apparatus by filling the 25 main supply chamber 15, its operation is entirely automatic; requiring no attention until the eggs are hatched.

I do not wish to be limited to the exact construction of parts which I have devised, 30 but desire that the claims which I make for my construction shall be construed in broad terms.

I claim:

1. In an incubator, the combination with 35 an outer fixed casing, a second casing vertically movable within the same, an egg receiver, a rotatable frame mounted freely above said receiver and forming egg turning means, and heating means suitably 40 mounted with respect to the casing, of means for automatically raising and lowering the vertically movable casing and rotating the egg turning frame, said means including a main liquid fuel supply, an auxiliary liquid 45 fuel supply in communication therewith and serving to feed the burner, an intermediate chamber receiving liquid fuel from said main liquid fuel supply which is subsequently passed to the auxiliary fuel supply, 50 a valve controlling the flow of liquid to and from said intermediate chamber, a piston in said intermediate chamber which is raised by the delivery of fuel thereto, a connection between said piston and the egg casing 55 whereby the latter may be raised, a connection between the egg casing operating means and the egg-turning frame whereby the latter may be rotated in one direction, and means for lowering the casing and effecting 60 rotation of the egg-turning frame in the opposite direction.

2. The combination with an incubator having an outer fixed casing, a movable casing within the same, and egg turning 65 means, of a body of fuel under head, a cham-

ber communicating therewith, a plurality of valves controlling the passage of fuel to said chamber, a piston in said chamber, a piston rod carried thereby, a connection between said piston rod and the movable casing 70 whereby the latter will be raised when said chamber fills with fuel, means operatively connected with the casing raising means for effecting movement of the egg turning means, a valve controlled by said piston, a second chamber, a piston therein for controlling the movement of one of the first-named valves, a third chamber, floats therein for controlling the movement of one of the first-named valves, pipes affording communication between said several chambers, certain of said pipes being arranged to by-pass certain of the valves, and a burner device in communication with and receiving fuel from said third chamber, said burner consuming 80 the fuel whereby movement of the several parts is automatically effected.

3. The combination with an incubator having an outer fixed casing, a movable casing within the same, and egg turning means, of a body of fuel under head, an auxiliary supply chamber communicating therewith, a plurality of valves controlling the passage of fuel from the main supply to said chamber, a piston in said chamber, a piston rod carried thereby, a connection between said piston rod and the movable casing whereby the latter will be raised when said chamber fills with fuel, means operatively connected with the casing raising means for simultaneously moving the egg turning means, a valve controlled by said piston, a second chamber, a piston therein for controlling the movement of one of the first-named valves, a third chamber, floats therein for controlling the movement of one of the first-named valves, pipes affording communication between said several chambers, certain of said pipes being arranged to by-pass certain of the valves, and a fuel consuming device in communication with and receiving fuel from said third chamber.

4. The combination with an incubator having an outer fixed casing, a movable casing within the same, and egg turning means, of a body of fuel under head, a temporary receiving chamber in communication therewith, valves controlling the passage of fuel to said receiving chamber, a piston in said chamber, a piston rod carried thereby, said piston being raised by liquid passed to said chamber, a connection between said piston rod and the movable casing whereby the latter will be raised by the movement of the piston, means operatively connected with the casing raising means for simultaneously moving the egg turning means, a valve controlled by said piston, a second chamber, a piston therein for controlling the movement of one of the first-named valves, a float 130

- 1 chamber for controlling the movement of one of the first-named valves, pipes affording communication between said several chambers, certain of said pipes being arranged to by-pass certain of the valves, and a burner device in communication with and receiving fuel from said float chamber.
5. In an incubator having a telescoping casing, the combination of a burner device for supplying heat, a fuel supply, a chamber intermediate the fuel supply and the heating device, means controlled by the consumption of such fuel for intermittently filling such chamber from the source of supply, 10 means for supplying fuel from said chamber to the heater, and means actuated upon the filling and emptying of said chamber for telescoping the casing.
6. In an incubator, the combination with a telescopic casing, an egg receiver therein, a turning device for said eggs, and a liquid fuel burning device for supplying heat, of a main fuel supply, an auxiliary liquid fuel supply 50, means including a plurality of 25 valves for controlling the filling and emptying of the latter, an intermediate chamber 19 receiving fuel from the said main fuel supply, means in said chamber 50 for closing one of said valves to effect the cutting off 30 of the supply of liquid fuel from the main supply to the intermediate chamber, a piston movable in said intermediate chamber by liquid passing to and from the same, means connecting said piston with the casing 35 whereby telescopic movement may be imparted thereto, means operatively connected with the casing moving means for effecting rotative movement of the egg turning device, and means for passing the fuel from 40 said auxiliary chamber to the burner.
7. In an incubator, the combination with an outer fixed casing, an inner casing, an egg receiver therein, means for turning the eggs, said inner casing being vertically movable, of a device for supplying heat, means for automatically supplying (liquid) fuel thereto including a temporary receiving chamber, rods connected to said casing, a plurality of pulleys, cords connecting said 50 rods and pulleys, a piston within said temporary receiving chamber actuated by the (liquid) fuel flowing to and from the same for operating said pulleys to raise and lower the casing, and means operatively connected therewith for simultaneously actuating the egg turning means.
8. In an incubator, the combination with a telescoping casing having an egg receiver therein, a burner device for supplying heat, and a main (liquid) fuel supply therefor, of an auxiliary (liquid) fuel supply, a chamber receiving fuel from said main fuel supply, a valve cutting off the supply of (liquid) fuel from the main supply to the 65 auxiliary supply, a piston within said chamber controlling the operation of said valve, means operatively connected with said piston for effecting telescopic movement of said casing, and means cooperating with said valve and controlled by the consumption of 70 such fuel for filling said auxiliary supply and chamber.
9. The combination with an incubator having an egg chamber within a telescopic casing, means for turning the eggs, and a liquid fuel heating device, of a body of liquid under head for delivery to said heating device, a delivery pipe therefor, valves controlling such delivery, a plurality of chambers receiving liquid, a by-pass to one of said 75 chambers around all of said valves, one of said auxiliary chambers communicating with the delivery pipe and first filling therefrom, a piston therein operatively connected to raise the telescoping casing and actuate the 80 egg turning means, means for operating one of said valves to cut off the flow of liquid to said auxiliary chamber, one of the first-named valves controlling such flow, means within said feed chamber for actuating one 85 of the valves to cut off the flow from the main body of liquid, said means being actuated upon the filling of said chamber, said heating device consuming the liquid from 90 said last named chamber, and means for releasing the valve-controlling means when such feed chamber empties.
10. The combination with an incubator having a telescopic casing, an egg receiver, means for turning the eggs in said receiver, 100 and means for effecting vertical movement of said casing and the actuation of said egg turning means, of a body of (liquid) fuel under head, an auxiliary chamber communicating therewith, valves controlling the 105 passage of (liquid) fuel to said auxiliary chamber, a piston within said chamber, a piston rod operatively connected thereto, means connecting said piston rod with the means to effect movement of the casing and 110 simultaneous movement of the egg turning device, a valve controlled by said piston, a second chamber, a piston therein for controlling the position of the valve 18 controlling the flow of liquid to and from said 115 auxiliary chamber, pipes for by-passing the liquid from the main supply to said second chamber, a third chamber, floats therein for controlling the movement of one of the first-named valves, and means in communication 120 with said third chamber for consuming the liquid therein.
11. In an incubator, including a casing forming a chamber, an annularly grooved egg support forming the bottom of the same, 125 a movable compartment frame for said eggs, a shaft, a pulley thereon, a vertical bearing for said frame, a pulley thereon, a cord leading from the shaft pulley to the pulley of the frame, of a body of liquid fuel under 130

head, means for effecting consumption of said fuel including an auxiliary chamber receiving fuel from the main supply and from which it is directly consumed, a chamber intermediate the main supply and said auxiliary supply which is intermittently filled, a piston in said chamber, and means operatively connecting said piston with said shaft whereby the latter may be turned to effect rotative movement of the egg turning means.

12. In an incubator, including a vertically movable telescoping casing forming a chamber, an annularly grooved egg support forming the bottom of said chamber, a movable compartment frame for said eggs, a shaft, of a body of liquid fuel under head, means for effecting consumption of said fuel in-

cluding an auxiliary chamber receiving fuel from the main supply and from which it is directly consumed, a chamber intermediate the main supply and said auxiliary supply which is intermittently filled, a piston in said chamber, and means operatively connecting said piston with said shaft whereby the latter may be turned to effect rotative movement of the egg turning means and simultaneous raising and lowering of the casing.

In testimony whereof, I have signed my name to this specification, in the presence of two subscribing witnesses.

ARTHUR E. ALLISON.
